US0D1112365S

(12) **United States Design Patent** (10) **Patent No.:** **US D1,112,365 S**
(45) **Date of Patent:** **** Feb. 10, 2026**

(54) **PUMP HEAD**

(71) Applicant: **Clik Corporation**, Westlake Village, CA (US)

(72) Inventors: **John Quintana**, Camarillo, CA (US); **John Walton**, Falmouth, ME (US)

(73) Assignee: **Clik Corporation**, Westlake Village, CA (US)

(**) Term: **15 Years**

(21) Appl. No.: **29/905,814**

(22) Filed: **Oct. 26, 2023**

Related U.S. Application Data

(63) Continuation-in-part of application No. 29/898,810, filed on Aug. 1, 2023, now Pat. No. Des. 1,069,685, and a continuation-in-part of application No. 18/132,038, filed on Apr. 7, 2023, and a continuation-in-part of application No. PCT/US2023/017843, filed on Apr. 7, 2023, and a continuation-in-part of application No. 18/121,947, filed on Mar. 15, 2023, now abandoned, and a continuation-in-part of application No. 18/106,745, (Continued)

(57) **CLAIM**

The ornamental design for a pump head, as shown and described.

DESCRIPTION

FIG. 1 is a perspective view of a pump head showing our new design;

FIG. 2 is a back view of the pump head shown in FIG. 1; FIG. 3 is a right side view of the pump head shown in FIG. 1;

FIG. 4 is a left side view of the pump head shown in FIG. 1; and,

FIG. 5 is a top view of the pump head shown in FIG. 1.

(Continued)

The broken lines in the drawings illustrate portions of the pump head that form no part of the claimed design.

1 Claim, 4 Drawing Sheets
